UNITED STATES PATENT OFFICE.

ADELINE JULIA MILLER, OF NEW YORK, N. Y.

DESIGN FOR A PENHOLDER ATTACHMENT.

SPECIFICATION forming part of Design No. 29,917, dated January 3, 1899.

Application filed December 10, 1898. Serial No. 698,917. Term of patent 14 years.

To all whom it may concern:

Be it known that I, ADELINE JULIA MILLER, a citizen of the United States, residing in the city of New York, (Brooklyn,) in the county of Kings and State of New York, have invented and produced a new and original Design for Penholder Attachments, of which the following is a specification, reference being had to the accompanying drawings, forming a part thereof.

In the accompanying drawings I have illustrated an embodiment of my new design, in which—

Figure 1 is a side elevation of the attachment; Fig. 2, an end view, and Fig. 3 a vertical sectional view, of the same.

The essential feature of my new design for penholder attachments embodies a tubular open-end portion of soft rubber adapted to surround the lower end of a penholder, and formed at the lower end of the tubular por-

tion is a guard portion surrounding and projecting from the same, the said guard portion having a concave upper face and a convex lower face.

Thus referring to the drawings, A designates the tubular portion of the attachment, and B the guard portion thereof, surrounding and formed integral therewith at one end of the tubular portion, the said guard portion having a concavity *a* in its upper face and being formed with a convex lower face.

What I claim is—

The design for a penholder attachment, substantially as shown and described.

In testimony whereof I have signed my name to this specification in the presence of two subscribing witnesses.

ADELINE JULIA MILLER.
